DESIGN FOR A WALL CLOCK

Lawrence C. Ludwig, Woodside, N. Y., assignor
to Keg-O-Klock, Inc., New York, N. Y.

Application May 4, 1933, Serial No. 48,009

Term of patent 3½ years

To all whom it may concern:

Be it known that I, LAWRENCE C. LUDWIG, a citizen of the United States, residing at Woodside, Long Island, county of Flushing, and State of New York, have invented a new, original, and ornamental Design for a Wall Clock, of which the following is a specification, reference being had to the accompanying drawing forming a part thereof.

Figure 1 is a front elevation of my new wall clock;

Figure 2 is a side elevation thereof; and

Figure 3 is a vertical longitudinal section therethrough.

My ornamental design for a wall clock includes the one end section of an actual beer or wine keg, the actual end wall of which forms the clock face, having studs and characters superposed thereon to complete the dial.

I claim:

The ornamental design for a wall clock as shown and described.

LAWRENCE C. LUDWIG.
